Attorney.

UNITED STATES PATENT OFFICE.

GEORGE ADAM SCHEHR, OF CINCINNATI, OHIO, ASSIGNOR TO THE CRANE & BREED MANUFACTURING COMPANY, OF CINCINNATI, OHIO, A CORPORATION OF OHIO.

HANDLE FOR BURIAL-CASKETS, &c.

SPECIFICATION forming part of Letters Patent No. 763,800, dated June 28, 1904.

Application filed February 27, 1903. Serial No. 145,452. (No model.)

To all whom it may concern:

Be it known that I, GEORGE ADAM SCHEHR, a citizen of the United States of America, and a resident of Cincinnati, in the county of Hamilton and State of Ohio, have invented certain new and useful Improvements in Handles for Burial-Caskets or the Like, of which the following is a specification.

This invention relates to certain improvements in handles of composite construction—such as are especially designed for use upon caskets, coffins, and the like and of which the handle shown and claimed in my pending patent application, Serial No. 134,842, filed December 8, 1902, is a type; and the object of the invention is to provide a handle of this general character of a simple, light, and inexpensive nature having reinforcing means of an improved and simplified construction by means of which the strength of the handle is greatly increased, so as to obviate accidental breakage thereof, the construction and arrangement of the several parts of the improved handle according to my invention being such that the increased strength is attained without making the handle clumsy or unsightly in its proportions and without unnecessarily increasing the cost of manufacturing the same.

The invention consists in certain novel features of the construction, combination, and arrangement of the several parts of the improved casket or coffin handle whereby certain important advantages are attained and the device is made simpler, cheaper, and otherwise better adapted and more convenient for use, all as will be hereinafter fully set forth.

The novel features of the invention will be carefully defined in the claims.

In the accompanying drawings, which serve to illustrate the invention, Figure 1 is a front elevation showing a casket or coffin handle constructed according to my invention; and Fig. 2 is a sectional view taken vertically through the pivotal connection of the swinging arm with the escutcheon-plate of the handle, the plane of the section being indicated by the line *a a* in Fig. 3. Fig. 3 is a sectional

view taken vertically and centrally through the handle in a plane at right angles to the plane of the section in Fig. 2, the swinging arm of the handle being in raised position and a portion of the wall of the casket or coffin being shown in section to illustrate the relation of the handle thereto. Fig. 4 is a view showing in front elevation the reinforcing member of the escutcheon-plate detached and enlarged, and Fig. 5 is a view showing the same part in side elevation. Fig. 6 is a view showing said reinforcing member as seen from its under or lower side. Fig. 7 is a perspective view showing the reinforcing member for the swinging arm detached and enlarged. Fig. 8 is a partial under side view showing, detached and enlarged, that end of the reinforce for the swinging arm through which is passed the hand-bar. Fig. 9 is a partial enlarged sectional view taken through the free end of the swinging arm at the lower side thereof and showing the means for anchoring the outer extremity of the reinforcing member thereof.

As shown in the views, the improved handle is made in a well-known style and comprises an escutcheon-plate adapted for attachment by means of screws to the side of a casket or coffin and a swinging arm held by a pivotal connection to the escutcheon-plate and having a circular loop at its free end adapted for the passage of a hand-bar to be grasped by the hand of a bearer in lifting and bearing the casket or coffin. There are commonly two escutcheon-plates and swinging arms employed in connection with each hand-bar, the hand-bar being extended between the swinging arms; but since the invention relates more especially to the improved construction of the escutcheon-plate and its swinging arm I have herein shown only these parts.

1 indicates as a whole the escutcheon-plate of the improved handle, and this plate is usually cast from soft metal, so that it may be plated and properly ornamented, and is formed with openings 2 for receiving screws for the attachment of the plate to the casket or coffin. The escutcheon-plate is for lightness hollowed

at its rear face; but at the points where openings 2 are located the rear surface is cast with lugs 3, through which the openings extend, the lugs being adapted to engage the side surface α of the casket, as indicated in Fig. 3. The central part of plate 1 has an outwardly-extended bearing portion or socket-piece 4 of rounded form, which is hollowed out, as seen at 5, to produce a chamber or socket, at opposite sides of which are produced lugs 6 6, spaced apart, as seen at 7, and perforated for the passage of a pivot-pin 8, whereon is pivotally held the swinging arm 9, the pivotal end 10 of which is received in the chamber or socket 5 and the outer free end of which is formed with a circular ring or loop 11, through which is passed the hand-bar 12, as shown in Figs. 3 and 9. The pivotal end 10 of the swinging arm is made rounded or semi-spherical at its upper part to fit snugly in the opening or socket 5 and to play therein when said arm is moved pivotally, the structure being such that said end of the arm fills and closes the socket at all times. At its pivotal point the arm 9 is made in reduced thickness, being recessed at opposite sides, as shown in Fig. 2 of the drawings, and the lugs 6 6 at opposite sides of the socket 5 are made to extend toward each other within said socket, so as to be adapted to enter the above-mentioned recesses at opposite sides of the arm 9.

The escutcheon-plate 1 is provided with a reinforcing or strengthening member 13, which is in the manufacture of said plate embedded in the soft-metal body portion thereof. The reinforcing member 13 has an arched upper part 14 extended across the rounded upper side of the socket 5, in which the pivotal end of arm 9 engages, and said arched part is extended across through the escutcheon-plate from the rear surface thereof, where its rear edge is adapted to bear against the side surface α of the casket or coffin to which the handle is secured, to the front surface of the socket portion 4 of the plate 1, so that when arm 9 is raised the strains imposed in lifting and bearing the casket or coffin will be exerted on the said arched portion 14 of the reinforce and will be transmitted by it to the side surface α of the casket or coffin instead of being imposed upon the soft-metal body portion of the escutcheon-plate, which would be thereby crushed and broken.

The member 13 is formed from sheet metal of suitable strength—such as sheet-steel, for example—and has side portions 15 15 extended down from the arched upper part 14 and at the opposite sides of the socket 5 and provided with forwardly-extended perforated lugs 16 16, embedded in the soft-metal lugs 6 6, which project toward each other at the sides of said socket 5. So far as described the construction of the handle is similar to that shown and claimed in my above-mentioned

to such features as are shown and described therein; but in carrying out my present invention the said lugs 16 of the sheet-metal reinforce are extended or bent toward each other so that they may stand when the arm 9 is in place as closely adjacent to the sides of the arm as possible to reduce the bending strains upon the pivot-pin 8 whereby the arm is held to the escutcheon-plate.

Below the lugs 16 16 the side portions 15 15 of the reinforce 13 are formed with extended portions 18 18 of reduced width, which are twisted and provided with perforated and enlarged end portions 17 17, which are bent slightly away from each other and extend in a plane at right angles to the planes in which the side portions 15 of the reinforce extend. These enlargements are embedded in the lower part of the plate 1 below the socket-piece 4 and have their perforations alined with the openings 2 2, through which are passed the screws for holding the plate 1 to the casket or coffin, so that when the screws are inserted in the openings 2 the steel arch-brace or reinforcing member 13 will be securely held in place upon the side of the casket or coffin with the rear edge of its upper arched part 14 bearing against the side surface α thereof.

The arm 9 is usually formed from cast soft metal also, so that it may be plated and ornamented with any desired design, and within it is embedded a reinforcing or strengthening member 19, also preferably formed from sheet-steel or other strong material, having a perforation through which the pivot-pin 8 extends and having a portion 20 within the pivotal end portion 10 of the arm and adapted to bear against the shoulder produced in the escutcheon-plate at the base of the socket 5 when the arm 9 is raised, as shown in Fig. 3. The pivotal end of the arm 9 has a shoulder upon its upper or front side, which shoulder is adapted when the arm is raised to engage upon the front surface of the projecting socket portion 4 of plate 1, and within said shoulder the member 19 has a projecting portion 21, as clearly shown in the drawings. The opposite free end of the member 19 is extended along the length of the arm 9 and is adjacent to the loop 11 thereof twisted upon itself, so that the extremity of the reinforce 19 extends in a plane at right angles to that portion wherein the opening for pivot-pin 8 is formed, the bent or twisted part being shown at 22, and the said extremity of the member 19 is bent into a circular or rounded form, as shown at 23, and is extended around and embedded in said loop 11 at the end of the arm 9, so as to reinforce and strengthen the same at the point where the arm receives the hand-bar 12. The extreme end 24 of the member 19 is spaced away from the part thereof at which the bend 22 is formed, and said end has its opposite side or edge portions formed with notches or recesses 25 25, as

shown in Figs. 3, 7, and 8, in which the soft metal of the arm 9 is adapted to run when the same is cast, so as to anchor and hold said end of the reinforce 19 in position. By means of 5 the notches or recesses 25 the portion of the member 19 beyond said notches is caused to project at opposite sides of the member, and the lateral projections thus formed engage the soft cast metal of the arm to effect- 10 ily anchor the member 19 therein. At a point beyond the notches 25 the said end of the reinforce 19 is also formed with a centrally-arranged slotted or elongated opening 26, in which the soft metal of the arm is also 15 adapted for a similar purpose to run when the same is cast, and in the soft metal within said opening 26 of the reinforce is adapted to be passed a screw for holding the hand-bar securely within the loop of the arm 9, as shown 20 in Fig. 9, wherein 27 indicates the soft metal within the opening 26 of the reinforce 19, and 28 represents the screw passed through such soft metal and engaged at its inner end with the hand-bar 12.

25 The construction of the improved casket or coffin handle with the improved strengthening means for its escutcheon-plate and swinging arm as herein set forth is extremely simple and inexpensive and is especially well 30 adapted for use, since it affords a very considerable increase in the strength and rigidity of the structure, so that accidents from breakage or crushing of the parts of the handle are avoided. The lugs 16 of the steel arch-brace 35 35 of the escutcheon-plate being bent toward each other add materially to the strength of the structure, since these lugs 16 are thereby embedded in the portions of the lugs 6 which project toward each other in socket 5 40 and engage in the recesses at the pivot-point of arm 9, the bent portions of lugs 16 being thus brought closely adjacent to the sides of the thinnest portion of the swinging arm, so that there is less liability of the pivot-pin 8 45 being bent or broken, and the anchoring of the free outer extremity 24 of the reinforce for the arm 9 serves to prevent straightening of the curved end of said reinforce, whereby the connection of the arm 9 with the hand- 50 bar would be destroyed and the handle broken.

It will also be obvious from the above description that the improved handle constructed according to my invention is capable of considerable modification without material 55 departure from the principles and spirit of the invention, and for this reason I do not wish to be understood as limiting myself to the precise form and arrangement of the device herein set forth in carrying out my in- 60 vention in practice.

Having thus described my invention, what I claim, and desire to secure by Letters Patent, is—

1. A casket or coffin handle having an escutcheon formed with a socket and having at 65 the sides of the socket lugs extended in the same, said escutcheon comprising a soft-metal body and a reinforce embedded therein around the upper part of the socket with perforated lugs within the lugs at the sides of the socket, 70 the perforated lugs of the reinforce being bent and extended toward each other and being positioned at the adjacent sides of the lugs of the escutcheon-plate, a swinging arm having an end engaged in the socket and having at its 75 sides recesses in which the lugs of the escutcheon are engaged and a pivot-pin passed through the swinging arm and through the perforated lugs of the escutcheon-reinforce.

2. A casket or coffin handle comprising an 80 escutcheon-plate having a socket provided with perforated lugs at opposite sides, a pivot-pin extended across the socket and held at its ends in the lugs, a swinging arm formed from soft metal and having one end held on the 85 pivot-pin and engaged in said socket, the other end of the arm having a loop adapted to receive a hand-bar, and a hard-metal reinforcing member embedded in the soft-metal arm and extended from the pivotal end there- 90 of to and around the loop and having an ex- tremity arranged at the under side of the loop and provided with recesses in which the soft metal of the arm is engaged to anchor said extremity and prevent straightening of the 95 same, substantially as set forth.

3. A casket or coffin handle comprising an escutcheon-plate having a socket provided with lugs at opposite sides, a pivot-pin ex- 100 tended across the socket and held in said lugs, 105 a swinging arm of soft metal held on the pivot- pin and engaged in the socket, the free end of the arm having a loop to receive a hand-bar, a hard-metal reinforcing member embedded in said arm and extended from the pivotal 110 point to and around the loop thereof and hav- ing its extremity arranged at the under side of the loop and provided with a perforation through which the soft metal of the arm is passed, and a screw passed through the soft 115 metal of the arm within said perforation and adapted for engagement with the hand-bar within the loop to hold the same to the arm, substantially as set forth.

Signed at Cincinnati, Ohio, this 24th day of 115 February, 1903.

GEORGE ADAM SCHEHR.
